SUPPORTING FRAME FOR POLISHING APPARATUS

Joseph L. Genaro, Knightstown, Ind., assignor to
Shur Brite Wax-O-Matic, Inc.

Filed June 28, 1971, Ser. No. 157,785

Term of patent 14 years

Int. Cl. D15—05

U.S. Cl. D49—12

Fig. 1

Fig. 2

Fig. 3

Fig. 4

FIG. 1 is a perspective view of a supporting frame for polishing apparatus showing my new design, and directed downward and toward the front of the frame;

FIG. 2 is a top view of said frame;

FIG. 3 is a rear view of said frame; and

FIG. 4 is a side view of said frame.

I claim:

The ornamental design for a supporting frame for polishing apparatus, as shown.
